United States Patent Office

Des. 191,910
Patented Dec. 12, 1961

191,910

PISTOL HOLSTER

Kasmir Simons, 10960 Church St., Chicago, Ill.

Filed May 8, 1961, Ser. No. 65,052

Term of patent 14 years

(Cl. D30—1)

Fig. 2.

Fig. 1.

Fig. 5.

Fig. 3.

Fig. 4.

Fig. 6.

FIG. 1 is a front elevational view of a pistol holster showing my new design;
FIG. 2 is a top plan view thereof;
FIG. 3 is a bottom plan view thereof;
FIG. 4 is a back view thereof;
FIG. 5 is a view of one end thereof; and
FIG. 6 is a view of the other end thereof.

I claim:

The ornamental design for a pistol holster, substantially as shown.
